UNITED STATES PATENT OFFICE.

LADIMIR F. STUPECKY, OF MANITOWOC, WISCONSIN

CARBURETER.

1,262,997.

Specification of Letters Patent. Patented Apr. 16, 1918.

Application filed January 12, 1917. Serial No. 141,964.

To all whom it may concern:

Be it known that I, LADIMIR F. STUPECKY, a citizen of the United States, and a resident of Manitowoc, in the county of Manitowoc and State of Wisconsin, have invented a new and Improved Carbureter, of which the following is a full, clear, and exact description.

The object of the invention is to provide a new and improved carbureter arranged to automatically control the mixture of air and gasoline vapors according to the speed of the engine thus rendering the carbureter exceedingly economical when in use and insuring the formation of a correct explosive mixture under varying speeds of the engine.

In order to accomplish the desired result, use is made of a needle valve provided with an auxiliary air supply normally closed by the liquid fuel in the well of the carbureter and opened on a rapid consumption of the liquid fuel in the well in case the engine is running at a high speed.

A practical embodiment of the invention is represented in the accompanying drawings forming a part of this specification, in which similar characters of reference indicate corresponding parts in both views.

Figure 1 is a side elevation of a carbureter provided with the improved needle valve, parts being shown in section; and

Fig. 2 is an enlarged sectional elevation of the needle valve.

The carbureter illustrated in Fig. 1 is of a standard type, and consists essentially of a reservoir 10 containing the liquid fuel, such as gasoline, and connected by an orifice 11 with a feed well 12 opening into the mixing chamber 13, connected at one end with an air supply and at the other end with the manifold of the internal combustion engine to supply the latter with an explosive mixture. The orifice 11 is controlled by the point 14 of a needle valve 15 screwing in the nut 16 and provided at its upper end with a handle 17 to permit of conveniently turning the needle valve to cause its point 14 to open the orifice 11 more or less with a view to insure the desired flow of liquid fuel from the reservoir 10 into the well 12.

The needle valve 15 is provided with an auxiliary air supply more especially designed for admitting air to the feed well 12 in case the liquid therein is consumed in excess of the amount supplied by way of the orifice 11

and the needle valve 14, that is, at the time the engine is running at a higher rate of speed than normal speed. The auxiliary air supply on the needle valve 15 is preferably formed by making the needle valve hollow to provide a duct 18 into the upper end of which open ports 19 leading to the atmosphere. The lower end of the passage 18 is provided with a series of apertures 20 arranged one above the other and extending within the well 12, as will be readily understood by reference to Fig. 1. It will be noticed that when the amount of liquid fuel in the well 12 decreases owing to a rapid consumption of such fuel then the uppermost of the apertures 20 is uncovered and consequently air can pass by way of the passage 18 into the well 12 and into the mixture, thus rendering the same lean. In case the engine speed remains high the further rapid consumption of gaseous fuel in the well 12 causes the next following aperture 20 to be uncovered, and so on, to supply more air to the well and thus render the explosive mixture correspondingly leaner. On the reduction of the speed of the engine the well 12 gradually fills again with liquid fuel which latter then gradually covers the apertures 20 until all are sealed by the liquid fuel.

The air supplied to the passage 18 is preferably pre-heated, and for this purpose the ports 19 open into a casing 21 held on the upper end of the needle valve 15, as plainly shown in Fig. 1. The casing 21 is connected with one end of an air supply tube 22, preferably wound around the exhaust pipe 23 of the internal combustion engine on which the carbureter is used so that the air passing through the pipe 22 is heated prior to passing into the passage 18 and the well 12.

It is understood that by the use of the hot air supplied to the feed well 12 a rapid evaporation of the liquid fuel is obtained. It is also understood that the air readily flows through the passage 18 as soon as the uppermost aperture 20 is uncovered owing to the suction action of the engine.

Having thus described my invention, I claim as new and desire to secure by Letters Patent:—

1. In a carbureter, a needle valve for regulating the fuel provided with a longitudinal air passage, a casing mounted upon the needle valve to admit of the latter moving there-

in and in communication with the air passage thereto, and a pipe connected with said casing for supplying fluid thereto.

2. In a carbureter, a fuel controlling needle valve having a longitudinal air passage therein and a lateral opening near its outer end leading from said passage, a casing

mounted upon the valve without interfering with its free movement and in communication with the air passage thereof through ¹⁰ the lateral opening, and a pipe connected with the casing for supplying fluid thereto.

LADIMIR F. STUPECKY.
